Primary Examiner — Khawaja Anwar
Assistant Examiner — Taylor O Mortorff**CLAIM**

(57) The ornamental design for a roller-type cleaning apparatus, as shown and described.

DESCRIPTIONFIG. 1 is a top perspective view showing my new design;
FIG. 2 is a front view thereof;

FIG. 3 is a rear view thereof;

FIG. 4 is a right view thereof;

FIG. 5 is a top view thereof;

FIG. 6 is a bottom view thereof;

FIG. 7 is an exploded view thereof; and,

FIG. 8 is a left view thereof.

The broken lines in the drawings illustrate portions of the roller-type cleaning apparatus which form no part of the claimed design.
